CLAIM

We claim the ornamental design for tray for use in a container, as shown.

DESCRIPTION

FIG. 1 is a perspective view of a tray for use in a container;

FIG. 2 is a view from one end of the tray;

FIG. 3 is a view from the other end of the tray;

FIG. 4 is a view from one side of the tray;

FIG. 5 is a view from the other side of the tray;

FIG. 6 is a top view of the tray;

FIG. 7 is a bottom view of the tray; and,

FIG. 8 shows the use of the tray in a container.

The broken lines are shown for illustrative purposes only and form no part of the claimed design.
